UNITED STATES PATENT OFFICE

111,106

DESIGN FOR A LAWN MOWER

Richard D. Clemson, Middletown, N. Y.

Application July 13, 1938, Serial No. 78,453

Term of patent 14 years

To all whom it may concern:

Be it known that I, Richard D. Clemson, a citizen of the United States, residing at Middletown, New York, have invented a new, original, and ornamental Design for a Lawn Mower, of which the following is a specification, reference being had to the accompanying drawings which form a part thereof.

Fig. 1 is a perspective view showing the front and one side of the mower of my new design; and

Fig. 2 is a perspective view showing the rear and one side of the mower.

The dominant features of my design reside in the portions illustrated in solid lines.

This application is a continuation in part of my copending application Serial Number D-76,105, filed March 26, 1938.

I claim:

The ornamental design for a lawn mower, substantially as shown and described.

RICHARD D. CLEMSON.
